MOLD COOLING DEVICE FOR LINE CASTING MACHINES

Filed Oct. 5, 1929

Fig. 1.

UNITED STATES PATENT OFFICE

SAMUEL E. SPERRY, OF HOLLIS, NEW YORK, ASSIGNOR TO INTERTYPE CORPORATION,
OF BROOKLYN, NEW YORK, A CORPORATION OF NEW YORK

MOLD-COOLING DEVICE FOR LINE-CASTING MACHINES

Application filed October 5, 1929. Serial No. 397,627.

The present invention relates to improvements in line casting machines such as those employing a mold for casting type bars or slugs against lines of matrices, and the primary object is to provide novel and improved means for cooling the molds used in machines of this class whereby increased speed of operation of the casting mechanism may be attained and the type bars produced will be solid or free of air holes and other imperfections.

Devices for cooling the molds of line casting machines have been heretofore proposed, such for example as by running water through channels provided in the mold wheel or carrier adjacent to the pockets in which the molds are set, and it has also been proposed to direct a jet of air against a portion of the mold or mold cap, but none of the devices heretofore proposed has fully met the demands of modern line casting machines, especially when molds are used for casting large or heavy bodied type bars, such molds absorbing and retaining considerable heat and it having become necessary in some instances to reduce the speed of operation of the casting mechanism in order to afford more time for the cooling of the mold after the casting of each type bar to insure the casting of type bars which are sufficiently solid or free of air holes or other imperfections which, if present, weaken the type bars so that they are liable to cave in or collapse under the heavy printing pressures in modern printing.

The present invention provides means whereby a blast of air is directed against the entire rear face of the mold and through the cavity in the mold in which the type bars are cast, the relatively large area thus acted on by the air blast insuring sufficiently rapid removal of heat from the mold to enable the casting mechanism to operate rapidly and to produce type bars which are solid and otherwise free from imperfections, especially

when molds are used for casting large or heavy bodied type bars, and it provides means, conveniently operable preferably from the front of the machine, for throwing the cooling device into and out of operation as desired, thus enabling the cooling device to be operated while a mold for the casting of the large or heavy bodied type bars is in use and to be thrown out of operation when a mold for the casting of small or thin bodied type bars which does not require cooling, is in use.

Another object of the invention is to provide a novel and improved cooling device of this kind which may be applied inexpensively to line casting machines as usually constructed without requiring extensive modifications or alterations of the machine, and to provide a cooling device of this kind which will consume a minimum amount of power from the driving motor of the machine.

To these and other ends, the invention consists in certain improvements and combinations and arrangements of parts all as will be hereinafter more fully described, the features of novelty being pointed out particularly in the claims at the end of the specification.

In the accompanying drawing:—

Fig. 1 is a fragmentary perspective view of portions of a line casting machine showing the improved cooling device applied thereto;

Fig. 2 is a side elevation, partly in section, of a portion of the machine showing the cooling device thereon;

Fig. 3 represents a horizontal section taken on the line 3—3 of Fig. 2, looking in the direction of the arrows; and

Fig. 4 is a fragmentary sectional view, the section being taken on the line 4—4 of Fig. 2 and looking in the direction of the arrows.

Similar parts are designated by the same reference characters in the different figures.

Cooling devices embodying the present invention are applicable generally to the molds of line casting machines of various kinds. In the present instance the cooling device in its preferred form is shown applied to a line casting machine of the class disclosed in U. S. Letters Patent No. 436,582 granted Sept. 16, 1890 to O. Mergenthaler, such machines as commonly constructed embodying a column-like main frame 1 having horizontal cross bars 2 at the sides thereof, a mold wheel slide 3 which reciprocates in a forward and rearward direction in guides formed at one side of the frame 1, and a mold wheel 4 which is carried on the mold wheel slide and has pockets therein into which are fitted a suitable number of molds each comprising a body 5 and a cap 6, the mold slide and mold wheel being movable forwardly in the machine to bring the front face of the mold into contact with the line of matrices against which the type bar is to be cast, the mold having a slot or cavity 7 in which the body of the type bar is cast, all as is well known to those familiar with machines of this class.

Also, in machines of this class, after a type bar has been cast in the mold, the mold wheel is rotated to bring it into vertical position where the type bar is ejected from the mold by an ejector blade 8 which is guided to reciprocate in a forward and rearward direction in guides formed in the mold wheel slide 3 after the slot or cavity 7 in the mold has been brought into alignment with the ejector blade 8. The ejector blade is guided at its forward end by a guide cap 9 which is usually formed separately from the mold wheel slide 3 and fixed thereto by screws and an ejector slide shield 10 is commonly attached to the mold wheel slide over the guide cap 9, the rear side of the mold wheel being commonly recessed to accommodate the forward end of the mold wheel slide so that the guide cap 9 and shield 10 will lie in close proximity to the rear face of the mold while the latter is in ejecting position, as will be clear from Fig. 3.

In applying the present invention to line casting machines of this class, the forward outer corner of the guide cap 9 is bevelled to form an inclined surface 11 which is directed substantially in line with the mold slot or cavity 7, and since the ejector slide shield 10 is spaced from the guide cap 9, a passageway 12 is formed between these parts which leads from the rear thereof to the rear face of the mold and the casting slot or cavity therein, and means is provided for supplying a blast of air to this passage so that the air will flow over substantially the entire rear face of the mold, including the body and cap thereof, and some of the air will flow forwardly through the mold slot or cavity 7 after the type bar cast therein has been ejected.

The means preferably employed for supplying the air blast in the manner described consists of an air blower which comprises a revoluble bladed runner 13, a circular housing 14 in which the runner operates, the housing having inlets 15 in a side thereof through which air enters the housing to reach the runner, and a discharge conduit 16 leads from the runner housing and terminates in a vertically elongated and horizontally constricted mouth 17 the vertical length of which approximately equals the length of the mold, the mouth 17 being off-set to bring it into a position where it will register with the rear end of the passage 12 which extends forwardly between the guide cap 9 and shield 10, so that the air blast produced by the rotation of the runner will be conducted through the conduit 16 and discharged at high velocity and in the form of a sheet through the flared mouth 17, this sheet of air being received directly by the air passage 12 and conducted thereby to the rear face of the mold. The air passage 12 flares toward the mold, due to the bevel 11, so that a considerable portion of the rear face of the mold and also the casting slot or cavity therein will be exposed directly to the air flowing forwardly in the passage 12, but since a clearance space is left between the rear face of the mold and the forward end of the mold wheel slide 3, the guide cap 9 and the shield 10, outlet passageways will be formed at these points which will permit air from the passage 12 to reach the rest of the rear surface of the mold body and cap, so that substantially the entire rear face of the mold is exposed to the cooling effect of the air blast, and after ejection of the type bar from the mold, part of the air blast will flow through the mold to cool it interiorly.

The air blower may be conveniently mounted in line casting machines as commonly constructed by forming its housing or casing with a lower flange 18 to bear against the inner side of one of the cross members 2 of the main frame and forming the blower housing with an arm 19 which extends upwardly therefrom and is formed with a hook-like portion 20 adapted to fit over the upper edge of an adjacent cross member 2 of the main frame and to engage the outer side of this cross member, screws 21 being extended through the flange 18 and secured to the respective frame cross member 2 to secure the flange 18 to the machine frame and a screw 22 being threaded in the upper arm 19 and arranged to bear against the inner side of the respective frame cross member 2 so that when this screw is turned in the proper direction, it will draw the outer end of the hook-like portion into engagement with the outer side of the respective frame cross member 2, the blower being thus rigidly secured to the machine frame.

secured in position within the frame of the machine.

The runner 13 of the blower, which may be of any suitable type such for example as those used in vacuum cleaners but which preferably embodies blades which have scoop-shaped portions 13^a on their edges adjacent to the air intake openings 15 of the housing to increase the suction of air into the blower, is revolved in the proper direction and at appropriate speed by a shaft 23 which is connected to the runner shaft by a universal joint 23^a, the runner shaft being journaled in bearings 24 in the blower housing, so that precise positioning of the blower housing in the frame of the machine is rendered unnecessary. The other end of the shaft 23 is journaled in a bearing 25 mounted in fixed position on the opposite side of the main frame 1, and it has a belt pulley 26 fixed to it by means of which it is driven.

The blower is driven during the operation of the machine preferably by belts from the main belt pulley 27, commonly used on machines of this class. In such machines, the pulley 27 is connected to a belt pulley 28 fixed on a so called intermediate shaft 29 by a belt 30, and the blower is driven from an additional belt pulley 31 which may be fixed to the shaft 29, this pulley being connected by a belt 131 to a belt pulley 32 which is fixed to a larger belt pulley 33, and the belt pulley 33 being connected to the driving pulley 26 on the blower shaft 23 by a belt 34.

During the operation of the line casting machine, the belt pulley 27 runs continuously. However, means is provided for interrupting the operation of the blower, if desired during the casting of relatively thin or small bodied type bars which may not require cooling of the mold. Preferably, this is accomplished by mounting the belt pulleys 32 and 33 on the rear end of a lever 35, this lever being pivoted to rock on the bearing 25 and about the axis of the shaft 23, the lever extending forwardly to the front of the machine where it is provided with a handle 36 by means of which it may be operated from the front of the machine. By so mounting the belt pulleys 32 and 33, the belt pulley 32 will be moved away from the belt pulley 31 when the lever 35 is swung upwardly or into the full line position shown in Fig. 2, thereby tensioning the connecting belt 131 and causing the blower to be driven from the shaft 29, and a downward swing of the lever 35 toward or into the dotted line position will move the belt pulley 32 toward the pulley 31, thereby producing sufficient slack in the connecting belt 131 to interrupt the drive of the blower. The lever 35 is preferably provided with a spring actuated plunger 37 the nose of which is adapted to seat in either of two properly located recesses 38 in the adjacent side of the frame of the machine so that the

lever 35 will be yieldingly retained in either of its positions, according to whether the blower is in or out of operation.

While the mold cooling device is in operation during the operation of the line casting machine, the air blast induced by the rotation of the fan or runner of the blower is projected from the flared discharge mouth of the blower into the passage provided in the forward end of the mold wheel slide, and this passage confines the air current and directs it against the rear face of the mold and into the mold slot thus causing heat accumulated in the mold due to the repeated casting of type bars therein, to be carried away from the mold, thereby maintaining the mold sufficiently cool to insure the casting of solid type bars free of air holes or other imperfections, especially when molds for casting large or thick-bodied type bars are in use. Since the mold wheel and its slide shift together forwardly and rearwardly in machines of this class in order to carry the mold to and from casting relation with the matrix line, the clearance space between the forward end of the mold wheel slide and the rear face of the mold will not vary so that the proper distribution of the air to the rear face of the mold by the air confining and directing passage or channel at the forward end of the mold wheel slide is not interfered with, although the discharge mouthpiece of the blower will be spaced sufficiently in rear of the guard on the mold wheel slide to avoid striking it when said slide is retracted.

By modifying the usual mold slide of the machine as hereinbefore described so that it may be used as a means for forming a channel to confine the air and conduct it to the mold, the construction is simplified and rendered readily applicable to line casting machines as heretofore commonly constructed, and by mounting the air blower on the frame of the machine as hereinbefore described, the application of this part of the mold cooling device to such machines may be accomplished with facility. The preferred driving means for the blower as shown is also simple and efficient, it taking its power from shafts already used in machines of this class, and it provides simple means for rendering the mold cooling device inactive when molds for casting small or thin-bodied type bars are in use.

I claim as my invention:—

1. In a line casting machine having a mold provided with a cavity for casting type bars therein, an air blower having a discharge mouth opposite to the rear face of the mold for directing a blast of air against the rear face of the mold substantially in the plane of the mold cavity.
2. In a line casting machine having a mold provided with an elongated cavity for casting a type bar therein, an air blower having

a discharge mouth which is flared in the direction of the length of said mold cavity and is opposite thereto and to the rear face of the mold.

5. In a line casting machine having a mold, ejector guiding means having a passage therein leading to the rear face of the mold, and means for inducing a flow of air through said passage toward the mold.

10. 4. In a line casting machine having a mold provided with a slot for the casting of a type bar therein, and ejecting means at the rear of the mold for ejecting type bars cast in said slot, ejector guiding means forming an air passage leading to the rear face of the mold and slot therein, and an air blower for forcing air through said passage and slot.

20. 5. A line casting machine comprising a mold wheel carrying a mold having a slot for the casting of a type bar therein, a mold wheel slide carrying means for ejecting type bars from the mold slot, said slide having a portion adjacent to the rear face of the mold provided with a passage which is elongated in the direction of the length of the mold and leads to the rear face thereof and the slot therein, and means for forcing air through said passage toward the mold.

30. 6. In a line casting machine comprising a mold wheel carrying a mold for casting type bars and a mold wheel slide carrying means for ejecting type bars from the mold, an air blower having means for mounting it opposite to the mold wheel slide, said blower having a conduit leading therefrom and provided with a discharge mouth which is flared in the direction of the length of the mold and is opposite to the rear face thereof.

40. 7. In a line casting machine having a mold for casting type bars, an air blower for air cooling the mold, driving means for the blower embodying means for connecting and disconnecting it with respect to a source of power, and a controlling member extending to the front of the machine and acting on said driving means to set the blower into and out of operation.

50. 8. In a line casting machine having a frame, a mold wheel carrying a mold for casting type bars, a slide carrying the mold wheel and guided to reciprocate on the frame, and an air blower having an air discharge mouth at one side of said slide and in rear of the mold, said blower embodying a housing having portions engageable with the frame at the side thereof opposite to said slide and means for securing said portions of the blower housing to the frame.

60. 9. In a line casting machine having a mold for casting type bars, an air blower having a revoluble runner and a discharge mouth for directing air to the mold to cool it, and driving means for the blower comprising a driving pulley on the runner shaft, a lever pivoted on the runner shaft, a pulley carried by

70. said lever and belted to the pulley on the runner shaft, and a relatively fixed-axis driving pulley belted to the pulley on said lever, the lever having an operating portion extending to the front of the machine and the lever being swingable about the axis of the runner shaft to tighten and slacken the belt connecting the pulley on said lever and the fixed-axis driving pulley.

75. In testimony whereof I have hereunto set my hand.
